(57) CLAIM

The ornamental design for a watch as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a first embodiment of the watch;

FIG. 2 is a front view thereof;

FIG. 3 is rear view thereof;

FIG. 4 is a right-side thereof;

FIG. 5 is left-side thereof;

FIG. 6 is top view thereof;

FIG. 7 is a bottom view thereof;

FIG. 8 is a top view thereof with the band folded; and

FIG. 9 is a bottom view thereof with the band folded.

FIG. 10 is a front perspective view of a second embodiment of the watch;

FIG. 11 is a front view thereof;

FIG. 12 is rear view thereof;

FIG. 13 is a right-side thereof;

FIG. 14 is left-side thereof;

FIG. 15 is top view thereof;

FIG. 16 is a bottom view thereof;

FIG. 17 is a top view thereof with the band folded; and

FIG. 18 is a bottom view thereof with the band folded.

FIG. 19 is a front perspective view of a third embodiment of the watch;

FIG. 20 is a front view thereof;
 FIG. 21 is rear view thereof;
 FIG. 22 is a right-side thereof;
 FIG. 23 is left-side thereof;
 FIG. 24 is top view thereof;
 FIG. 25 is a bottom view thereof;
 FIG. 26 is a top view thereof with the band folded; and,
 FIG. 27 is a bottom view thereof with the band folded.
 The features shown in broken lines form no part of the claimed design.
